UNITED STATES PATENT OFFICE.

BENJAMIN W. DAVIS, OF CHICAGO, ILLINOIS.

RECEPTACLE FOR LIQUIDS.

1,326,853.

Specification of Letters Patent. Patented Dec. 30, 1919.

Application filed October 19, 1914. Serial No. 867,449.

To all whom it may concern:

Be it known that I, BENJAMIN W. DAVIS, a citizen of the United States, residing at Chicago, in the county of Cook and State of Illinois, have invented certain new and useful Improvements in Receptacles for Liquids, of which the following is a specification.

This invention relates to improvements in fluid receptacles, and has for its object to provide an improved form of receptacle in which the fluid may be quickly emptied therefrom without trouble, smooth pouring being insured by provision of means to prevent the formation of a partial vacuum in the interior of the can.

Another object is to provide means for supplying air to the interior of the can or receptacle when the same is partially tilted, when the same is fully tilted and during substantially the entire emptying whereby a smooth flow is insured in either or between either position of the receptacle, this means also being operable to permit exhaust of air from the can or receptacle when the same is being filled.

Still another object is to provide means for partially opening the fluid outlet should it be desired and to uncover or open the air supplying inlets simultaneously with the partial or full opening of the fluid outlet.

Still another object is to provide means to enable the user to seat the closing cap on the flange or neck of the outlet in position for the threads to immediately engage without preliminary rotation of the cap or closure.

Still another object is to provide an improved form of cap which may be readily sealed or locked to the ordinary handle of the receptacle.

These and other objects will be set forth and made apparent in the following specification and accompanying drawings, in which;

45 Figure 1 is a perspective view of an improved receptacle embodying my invention;

Fig. 2 is a plan view of a portion of the same showing the fluid outlet and air inlets;

Fig. 3 is a detail of the closure or cap;

50 Fig. 4 is a vertical section along the line 4-4 of Fig. 2;

Fig. 5 is a detail of one of the inlets;

Fig. 6 is a detail of the other of said inlets;

Fig. 7 is a detail of the neck or outlet flange;

Fig. 8 is a detail of a modification;

Fig. 9 is a plan view of the same;

Fig. 10 is a perspective of a can or receptacle embodying another form of my invention;

Fig. 11 is a side elevation partially in detail of the air inlet tube used in the form shown in Fig. 10;

Fig. 12 is a side elevation of a detail of the form shown in Fig. 10;

Fig. 13 is a plan view of the same;

Fig. 14 is a side elevation partially in section of the cap; and

Fig. 15 is a vertical section through the spout, cap, collar, etc., of the form shown in Fig. 10.

Like reference characters refer to like elements throughout the drawings.

In the form shown in Figs. 1 to 7, A designates a fluid receptacle or can of the common rectangular type having the fluid outlet or filler opening B surrounded by the neck or flange B' threaded for engagement by the usual cap or closure. A collar or flange C

75 is located around and spaced from the neck or flange B' and is provided with the spout portion c, formed therefrom to facilitate pouring of the fluid from the receptacle. The neck or flange B' is provided with the 80 outlet aperture b preferably located as closely adjacent the spout portion c as possible, as indicated in dotted lines in Fig. 2. Dished-out recesses or grooves d and e are provided in the space between the flange B' and the collar C. These dished-out grooves or recesses d, e are provided with apertures therein and securely fixed in these apertures are the air inlet pipes D, E,

85 respectively. These inlet pipes are arranged as clearly shown in dotted lines in Fig. 1, the inlet D extending from groove d to a point adjacent the top of the interior of the can or receptacle and opposite the fluid outlet. The other air inlet tube E extends from the groove or recess e to adjacent the bottom of the receptacle at a point also opposite the fluid outlet with respect to the vertical axis of the can or receptacle. The purpose of this construction will be explained below.

90 95 100 105 A cap or closure, generally indicated by F is threaded to engage the neck or flange B' and is provided at its lower portion with

the peripheral outwardly extending flange G, the external diameter thereof being slightly less than the smallest diameter of the collar C which tapers inwardly from its contact with the receptacle to its uppermost portion, as clearly shown in Fig. 4, for example. An annular groove or recess is provided in the flange G and a packing ring g is secured to the under-side of flange G adjacent its outer periphery. When the cap is screwed down on neck B' to closing position, the aperture b will be closed and the packing ring g of cork or the like having contacted with the surface of the receptacle between flange or neck B' and the collar C, outwardly of the grooves or recesses d, e, leakage of air or fluid under the flange G will be prevented, the natural resiliency of the flange G serving to maintain the packing ring g in closing position. A second flange H is secured to the cap F and extends outwardly therefrom, above the flange G and is of sufficient size to slightly project over the collar C when the cap is in closing or approximately in closing position, so that dust and dirt will be prevented from settling in the space between the collar C and flange B'. The cap F upwardly of the flange H is crimped or beaded, as indicated by f, thereby providing a groove between the flange H and the bead or crimp f in which is seated a fastening chain K which may be looped around and have its free end attached to the handle a of the receptacle. When the cap is in position, as shown in Fig. 4, the groove or bulge g' is located over the recesses or grooves d, e, and permits free admission of air to the inlet tubes when the cap is partially raised. The flange G is provided with the lug g'', projecting outwardly therefrom. This lug is so located with respect to the threads of the cap and outlet cover, that when the lug is placed in alinement with the pouring spout or portion c of collar C, the threads will be in engagement and proper rotation of the cap will result in the same being drawn to closing position without preliminary adjusting and manipulation of the cap to secure proper engagement of the thread. This lug g'' is so arranged and constructed that it will not permit placing of the cap in other than the position stated, since it projects out slightly beyond the top of the collar C so as to prevent screwing downwardly of the cap F when in other than the position stated. When in proper position, however, the drawing down of the cap will, by virtue of the pitch of the thread, cause the lug g'' to pass beneath the top of the collar C, permitting rotation of the cap to closing position, as shown in Fig. 4. This construction insures proper placing of the cap as stated above, and without preliminary manipulation thereof. When the receptacle contains

fluid and it is desired to pour the same out, the cap F may be rotated to partially open the opening b and the can or receptacle tilted, whereupon fluid which may be in the inlet tube D will flow therefrom into the space between the collar C and flange B' and flow out the spout portion c together with fluid flowing through the aperture b. As soon as a slight amount of fluid has poured from the can, the top of inlet tube D will be exposed and air will be admitted therethrough, preventing the formation of a partial vacuum in the can, thereby preventing the bubbling or jerking flow of the fluid as it is poured from the can so that smooth, uninterrupted flow is obtained. As the fluid is gradually poured from the can or receptacle, the latter is tilted more and more until finally the upper end of inlet E will be uncovered and air will be allowed to flow therethrough, supplementing or replacing the air supply of inlet D should that be covered by the fluid, so that in all positions of the can while the same is being emptied, air is supplied to the interior which insures an even and rapid flow of the fluid therefrom during the entire emptying of the can.

Furthermore, as stated above, the air inlets when emptied mingle their contents with those passing through the regular outlet b so as to concentrate all flow of fluid from the receptacle.

It will be apparent that by the construction of the receptacle outlet and the closure, immediate opening of the air inlets results in the partial opening of the fluid outlet so that air is admitted at all times to the receptacle when the same is being emptied.

I may form the flange H of cap F with the loop or apertured lug h adapted to lie adjacent the handle a of the receptacle when the cap is in closed position whereby the sealing strip L of metal or the like may be sealed, as shown in Fig. 1, in position engaging the handle a, lug h to prevent opening or emptying of the receptacle.

In Figs. 8 and 9 I have shown a slight modification, by means of which I am able to dispense with the collar C if so desired. An aperture c' is provided in the neck C' of the outlet and a small recess or cavity is formed back of the said aperture c' by means of the looped wall c'', shown in Fig. 9. The air inlet tube J leads therefrom and has one end secured in this cavity communicating with the exterior of the receptacle through the aperture c'. It will be apparent by this construction, as in the case of the other form a slight opening of the outlet aperture b by partial unscrewing of the cover or cap will permit air to flow in through aperture c' and through inlet tube J.

In Figs. 10 to 15 is shown another form of my invention. In these views L designates a can or receptacle having the outlet

passage M therein the same being also capable of use for filling. Extending upwardly from around this opening is the threaded flange or neck N and surrounding the same 5 is the groove O. This groove is provided with the slot or aperture O' therein. Spaced from and located around the neck N is the upstanding flange P provided with a pouring spout P' located as shown in the drawings. An air tube Q communicates with the groove O at Q' and extends therefrom to a point substantially diametrically opposite thereto in the receptacle L. This tube Q is provided with the enlarged elbow Q'' in 10 which is provided an aperture Q³ and a flange Q⁴ in which is provided an aperture Q⁵, see Fig. 11. The flange Q⁴ together with the outer wall of the elbow Q'' constitutes a race or passage for a ball R. Extending 15 downwardly from and communicating with the air tube Q is the tube S in communication with the receptacle L adjacent the bottom thereof and also substantially diametrically opposed to the discharge outlet of the receptacle. The apertures Q³ and Q⁵ and ball R are so arranged that when the can is partially tilted to pour the contents thereof from spout P', the ball R will be in the position shown in full lines in Fig. 11 and 20 air will be permitted to flow through tube Q and apertures Q⁵ and Q³ into the receptacle L for the purpose mentioned in connection with the embodiment shown in Figs. 1 to 7, and as the can is substantially half 25 tilted the ball R will roll to the position indicated in dotted lines in Fig. 11 shutting off aperture Q⁵ and when in this position air will be prevented from flowing through aperture Q³, also fluid will be prevented 30 from flowing into tube Q while air will flow therethrough and through tube S into the bottom of the receptacle, as will be obvious. By this construction I eliminate the necessity for two separate tubes as in the case of 35 the form shown in Fig. 1, for example, but attain the same end.

Coating with the neck N is the cap T comprising a threaded depending collar T', the outwardly extending top T'' and the intermediate outwardly extending flange T³ to which is attached a packing ring T⁴. When the cap T is in closing position this ring T⁴ will rest on and cover the groove O, as is shown in Fig. 15. I also provide a 50 packing strip T⁶ on the under side of T, this strip contacting with the top of neck N when the cover is in closing position. The wall P is outwardly bent, as indicated at P'', this providing a passage for air to the tube 55 Q beneath packing ring T⁴ when the cap T is partially unscrewed or raised from closing position as indicated by the arrow in Fig. 60 15. The aperture N' is provided in the wall N for pouring, and it will be apparent 65 that this will be partially uncovered as the

cap T is partially raised thereby permitting control of the fluid from the can or receptacle L. At the same time, as explained above, as soon as the cap and packing ring T⁴ is raised at all, air may flow through the passage formed by the bent portion P'' of wall P, thereby insuring smooth flow of the fluid. The packing ring T⁴ fits closely within the wall P and also serves to control the opening of the spout P', as will be apparent. 70 The aperture O' in groove O permits the draining of fluid from the tube Q, spout P' and groove O when the receptacle is returned to normal or up-right position after partial or full emptying thereof and also provides an additional outlet for fluid from the can, since this aperture O' will be covered by and furnish an outlet for the fluid when the can is tilted, owing to its location 75 adjacent the spout P'. 80

To provide for instant engagement of the threads of the cap T and neck N, I provide bosses or lugs U and V on the receptacle and cap, respectively and so arranged that alignment of such lugs when the cap is first placed on the neck will insure engagement of the respective threads and assist in ready fastening of the cover to the neck. I also provide the apertured lug T' on flange T'' so arranged that when the cover T is in closing 90 position a strip of sealing metal W, or the like, may be passed through the aperture therein and engage the handle L' of the receptacle to prevent wrongful extraction of the contents of the receptacle by thieves or 95 others. 100

It will be obvious that while I have described and shown my invention with more or less particularity, the same is susceptible of many modifications and changes and I do not wish to be restricted to the form shown and described beyond the scope of the appended claims. 105

What I claim is:

1. A fluid receptacle, a fluid outlet, an air inlet leading to the interior of said receptacle, and means to partially open said outlet without removal therefrom, said means being arranged to simultaneously open said inlet. 110

2. In a fluid receptacle, automatic means to supply air to said receptacle when the same is partially tilted, and means to supply air to said receptacle when the same is approximately fully tilted. 115

3. In a fluid receptacle, means to supply air to said receptacle near the top thereof when the same is partially tilted, means to supply air to said receptacle when the same is approximately fully tilted, both said means communicating with the exterior of said receptacle adjacent said fluid outlet and a common means for connecting the exterior communicating ends of each of said means. 125

4. A fluid receptacle having a fluid outlet 130

and air inlets the latter leading to points in said receptacle approximately diametrically opposed with respect to said fluid outlet and a common means for controlling said 5 outlet and inlet.

5. A receptacle having a flanged fluid outlet, a collar carried by said receptacle, said collar being located around and spaced from said flange, said collar being formed with 10 a pouring spout, said flange being provided with an aperture whereby fluid may be poured therethrough, and a closing means adapted to engage and coact with said flange to permit regulation of the discharge of 15 fluid through said aperture.

6. A receptacle having a flanged fluid outlet, a collar carried by said receptacle, said collar being located around and spaced from said flange, said collar being formed with 20 a pouring spout, said flange being provided with an aperture whereby fluid may be poured therethrough, a closing means adapted to engage and coact with said flange to regulate the discharge of fluid through 25 said aperture, an air inlet leading from the space between said flange and collar to the interior of said receptacle, and means carried by said closing means to open and close said air inlet as said fluid outlet is opened 30 or closed.

7. A receptacle having a flanged fluid outlet, a collar located around and spaced from said outlet, an air inlet leading from between said collar and flange to the interior 35 of said receptacle, and a closure for said fluid outlet engaging said flange, said closure being provided with means to open and close said air inlet, said means comprising an outwardly extending flange carried by said closure.

8. A receptacle having a flanged fluid outlet, a collar located around and spaced from said outlet an air inlet leading from between said collar and flange to the interior 45 of said receptacle, a closure for said fluid outlet engaging said flange, said closure being provided with means to open and close said air inlet, said means comprising an outwardly extending flange car-

died by said closure, and a second flange 50 carried by said closure and adapted to fit over said collar when said closure is in closing position.

9. A fluid receptacle having a discharge outlet, an air inlet tube extending from adjacent delivery opening of said outlet into said receptacle, said tube comprising angularly disposed portions, one of said portions being normally in communication with the upper interior of said receptacle, and the 60 other of said portions being in communication with the lower interior of said receptacle.

10. A fluid receptacle having a discharge outlet, an inlet tube extending from adjacent 65 said outlet into said receptacle, said tube comprising angularly disposed portions, one of said portions being normally in communication with the upper interior of said receptacle, the other of said portions being 70 in communication with the lower interior of said receptacle, said tube being provided with an aperture adjacent the junction of said angularly disposed portions, and means to prevent flow of fluid through said aperture and tube when said receptacle is sufficiently tilted.

11. A fluid receptacle having a discharge outlet, an inlet tube extending from adjacent said outlet into said receptacle, said 80 tube comprising angularly disposed portions, one of said portions being normally in communication with the upper interior of said receptacle, the other of said portions being in communication with the lower interior 85 of said receptacle, said tube being provided with an aperture adjacent the junction of said angularly disposed portions, and means to prevent flow of fluid through said aperture and tube when said receptacle 90 is sufficiently tilted, said means comprising a ball check adapted to close said aperture.

In testimony whereof I have subscribed my name.

BENJAMIN W. DAVIS.
